The figure is a plan view of a brassiere showing my new design.

The dominant feature of my design resides in a brassiere having a symmetrical wing-shaped front member with cups positioned in it, the member having an undulated bottom edge with each end terminating at substantially the horizontal median of the brassiere in an upwardly extending side seam and a top edge which extends inwardly and upwardly from each of said side seams at the horizontal median to the vertical median of each cup and then downwardly and inwardly meeting at the center of the brassiere to form a V between the cups, substantially as shown in the drawing.

I claim:

The ornamental design for a brassiere, as shown and described.
